DESIGN FOR A PULL WIND DESK CLOCK AND BASE COMBINATION

John P. Ambrose, Bronx, N. Y., assignor to Phinney-Walker Company, Inc., New York, N. Y., a corporation of New York

Application June 19, 1939, Serial No. 85,566

Term of patent 14 years

To all whom it may concern:

Be it known that I, John P. Ambrose, a citizen of the United States, residing at Bronx, county of Bronx, State of New York, have invented a new, original, and ornamental Design for a Pull Wind Desk Clock and Base Combination, of which the following is a specification, reference being had to the accompanying drawing, forming part thereof.

In the drawing, Fig. 1 is a front elevation and Fig. 2 is an end view of the pull wind desk clock and base combination, showing my new design.

I claim:

The ornamental design for a pull wind desk clock and base combination, substantially as shown.

JOHN P. AMBROSE.
